CARTON-SEALING MACHINE.

1,257,745.

Specification of Letters Patent. Patented Feb. 26, 1918.

Application filed October 15, 1915. Serial No. 56,012.

To all whom it may concern:

Be it known that we, ERNEST A. SCHROEDER and JOHN N. TOOKER, citizens of the United States, and residents of Syracuse, in the 5 county of Onondaga and State of New York, have invented a new and useful Improvement in Carton-Sealing Machines, of which the following is a specification.

This invention is directed to certain improvements in the construction, form, arrangement and operation of the several parts of a carton sealing machine whereby the cartons to be sealed are rapidly and accurately fed into position to have their open 15 tops closed and sealed and as rapidly and accurately delivered, the danger of the machine becoming clogged by the inaccurate feeding or delivery of the cartons being obviated.

20 The invention is further directed to a novel means for applying paste to one of the flaps at the open end of the carton and to novel means for folding and sealing the flaps without unduly delaying the carton in its 25 passage through the machine.

The invention is also directed to means whereby the carton with or without its wrapper may be successfully sealed without changing the parts of the machine.

30 The pasting mechanism is not specifically claimed herein, as it forms the subject-matter of a divisional application filed by us on March 14, 1917, Serial No. 154,807, for carton sealing machines.

35 A practical embodiment of our invention is represented in the accompanying drawings, in which—

Figure 1 is a view looking at one side of the machine, the paster mechanism being removed,

Fig. 2 represents the paster mechanism in side elevation,

Fig. 3 represents the machine in top plan,

Fig. 4 is a detail plan view showing the 45 carton and its adjacent parts in position to start the first folding operation,

Fig. 5 is a detail section taken in the plane of the line A—A of Fig. 4,

Fig. 6 is a detail end view of the parts 50 shown in Fig. 4,

Fig. 7 is a detail front view of the same,

Fig. 8 is a horizontal section taken in the plane of the line B—B of Fig. 6,

Fig. 9 is a view similar to Fig. 4 with the parts in the positions which they assume 55 when three of the flaps have been folded,

Fig. 10 is a detail end view of the same,

Fig. 11 is a detail front view of the same,

Fig. 12 represents the machine in elevation looking toward the carton feeding-in 60 end thereof,

Fig. 13 is a detail transverse section taken in the plane of the line C—C of Fig. 1,

Fig. 14 is a detail longitudinal section taken in the plane of the line D—D of 65 Fig. 13,

Fig. 15 is a detail sectional view showing the cam mechanism for controlling one of the flap closing devices,

Fig. 16 is a detail section showing the cams 70 for controlling one of the other flap closing devices, of which there are two, arranged in opposite relationship,

Fig. 17 is a detail section showing the cams for controlling the movement of the 75 carton ejecting device,

Fig. 18 is a view at the side of the machine opposite to that shown in Fig. 1,

Fig. 19 is a detail sectional view of the reciprocating device for feeding the cartons 80 longitudinally of the machine, the parts being in their released position,

Fig. 20 is a similar view with the parts shown in their closed position,

Figs. 21, 22, 23 and 24 disclose the various 85 steps in folding and sealing the open end of the filled carton, where the carton is provided with a wrapper, and

Figs. 25, 26, 27 and 28 disclose the various 90 steps in folding and sealing the open end of the filled carton, where the carton is not provided with a wrapper.

The main drive shaft of the machine is denoted by 1 and it is constantly driven, as, for instance, by the belt 2 and pulley 3, from 95 any suitable source of power not shown herein. This shaft 1 is mounted in suitable bearings in the arms 4, 5, of the paster frame 6. The upright paster shaft 7 is driven from the main drive shaft 1 through 100 the spiral gears 8, 9, which shaft 7 is mounted at its lower end in suitable bearings in

the arm 5 of the paster frame 6 and at its upper end in suitable bearings in the bracket 10 carried by the stationary upright bar 11 of the paster frame.

5 The paste transferring wheel 12 is fixed to the top of the shaft 7 and its periphery contacts with the face of the paste fountain disk 13, which disk is fixed to a shaft 14 mounted in the bracket 10. This fountain disk 13 is positively driven from the shaft 7 by the bevel gears 15, 16.

The paste fountain 17 is carried by an adjustable bracket 18 having arms 19, 20, slidably mounted on the stationary upright bar 11. A screw 21 engages the paster frame 6 and the arm 19 of the fountain bracket 18 for adjusting the fountain vertically to the desired position.

A sleeve 22 surrounds the main drive shaft 1, which sleeve is mounted in the arm 4 of the paster frame and is provided with a drive pulley 23 located at the side of the drive pulley 3 of the main drive shaft, which pulley 23 is driven by the belt 2 when the belt is in the position shown in full lines in Fig. 3. The drive of this pulley 23 may be discontinued by shifting the belt 2 onto the pulley 3, as shown in dotted lines in Fig. 3.

30 A cross shaft 24 is mounted in suitable bearings in the arm 4 of the paster frame 6 and on the main frame 25 of the machine, which shaft 24 is driven from the sleeve 22 through spiral gears 26, 27. Two longitudinally arranged cam shafts 28, 29, mounted in suitable bearings in the main frame 25 are driven from the cross shaft 24 through spiral gears 30, 31, 32 and 33, respectively.

40 A stud shaft 34, mounted in suitable bearings in the main frame 25, is driven through gears 35, 36, from the cross shafts 24, and the stud shaft 34 drives a crank shaft 37 through the mutilated gears 38, 39. A cam shaft 40, mounted in suitable bearings in the main frame, is also driven from the stud shaft 34 through the gears 41, 42.

The cam shaft 29 drives the upright shaft 43 mounted in suitable bearings in the main frame 25 at the feeding in end of the machine, through the bevel gears 44, 45, which upright shaft 43 drives at the desired speed through the spiral gears 47, 48, the shaft 49, of the belt pulley 50 around which the endless belt 46 travels.

55 The upright shaft 43 drives a longitudinally disposed shaft 51 mounted in suitable bearings in the main frame through bevel gears 52, 53 which shaft 51 in turn drives the short upright shaft 54 through the spiral gears 55, 56. The shaft 54 is mounted in suitable bearings in a carriage 57 slidably mounted on the longitudinally arranged rod 58 and the shaft 51. The upright shaft 43 reciprocates the carriage 57 through the crank 59 and pitman 60. The

upright shaft 54 is provided with the rotary arm 61 having the paste applying segment 62 arranged in position to engage the periphery of the paste transfer wheel 12 every revolution of the arm 61.

70

A skeleton guide, arranged longitudinally of the machine, is provided for the cartons as they are fed into the machine from the endless belt 46, which guide comprises the two side walls 63, 64, having inwardly turned bottom flanges 65, 66, along which the cartons travel from the feeding-in end of the machine to the table 67. This table 67 has a wall 68 against which the cartons are successively pushed by the carton advancing means.

75

The tops of the side walls 63, 64, of the skeleton guide are provided with converging guides 69, 69, for truing up the flaps at the open top of the carton as the carton 85 is forced from the skeleton guide into position on the table 67.

80

The carton advancing means is arranged to move the cartons intermittently along the skeleton guide and it is constructed and arranged as follows: Two longitudinally arranged stationary bars 70, 71, are located adjacent to the bottom of the skeleton guide. The hubs 72, 73, of two rocking levers are mounted on these bars between the ends 74, 96 75, of a reciprocating carriage 76 also mounted on these bars. A rod 77 connects the ends 74, 75, of the reciprocating carriage 76 and a wedge shaped cam 78 has a limited sliding movement on said rod 77.

100

The upper arms 79, 80, of the two rocking levers, carry blocks 81, 82, arranged to be brought into and out of frictional engagement with the opposite sides of the cartons through the side walls 63, 64, of the skeleton guide. The lower arms 83, 84, of the levers are arranged in position to be engaged by the movable wedge-shaped cam 78. This cam 78 has a depending lug 85 which is connected by a link 86 with the long arm 87 of a rocking lever pivoted at 88 to the main frame. This lever is rocked longitudinally of the machine by a cam 89 on the shaft 40, which cam engages a stud or roller 90 on the long arm 87 and a stud or roller 91 on the short arm 92 of the said lever.

105

The cartons are moved laterally off the table 67 onto the longitudinally reciprocating folding and sealing carriage 93 (to be hereinafter described), by the following mechanism, viz: A pusher 94 movable laterally of the machine over the table 67 is provided with an upper slide plate 95 slidable in grooves in the table 67 upon opposite sides of the elongated slot 67. A lower slide plate 96 is also slidable in grooves in the table 67 immediately below the upper slide plate 95. This lower slide plate is reciprocated laterally of the machine by a rocking

115

120

125

130

- lever, the long arm 98 of which is connected to the lower slide plate by a link 97. This lever is pivoted at 99 to the main frame and rocked outwardly by a cam 100 on the shaft 5 28 which engages a stud or roller 101 on the long arm 98 of the lever. The lever is rocked inwardly by a cam 102 on the shaft 28, which engages a stud or roller 103 on the short arm 104 of the lever.
- 10 Means are provided for interlocking the upper and lower slide plates 95 and 96, which means is under the control of the carton about to be pushed laterally from the table 67 onto the carriage 93. Said interlocking means comprises a rock lever pivoted at 105 to the main frame, the upper arm 106 of which lever projects normally a short distance beyond the wall 68 into position to be engaged by the carton and pushed back-20 wardly thereby when the carton is properly placed on the table 67 in front of the pusher 94.
- The lower arm 107 of the lever supports a laterally and vertically slidable locking pin 108. This pin slides vertically through the lower slide plate 96 and is arranged to be moved into and out of a hole 109 in the upper slide plate 95 by the movement of the carton controlled rocking lever.
- 30 The upper end of the pin, even when in its lowered position, projects slightly above the lower slide plate 96 and the upper slide plate 95 is provided with a depending lug 110 arranged back and in the path of travel 35 of the projecting end of the pin 108 so that the pin will, because of its engagement with said lug, always return the pusher 94 to the limit of its outward movement even though the pin be withdrawn from the hole 109 in 40 the upper slide plate by the release of the upper arm 106 of the carton controlled lever, thus permitting the free feeding of a succeeding carton onto the table 67 in front of the said pusher 94. This pusher 94 is provided with a flush side 111 for closing the 45 delivery end of the skeleton guide while the carton on the table 67 is being moved off therefrom.
- The flap folding and sealing carriage 93 50 heretofore referred to, reciprocates longitudinally of the machine on the shaft 29 and in the tracks 112, 113, of the main frame. The carriage is reciprocated through the pitman 114 and the crank 115 of the shaft 55 37. A considerable dwell is provided for the carriage at both limits of its movement by the co-action of the mutilated gears 38, 39, to permit the carton to be pushed onto the top of the carriage when the carriage 60 is at the limit of its movement toward the feeding-in end of the machine and to be pushed off from the top of the carriage when the carriage is at the limit of its movement toward the delivery end of the machine.
- 65 A pocket is provided on the top of the carriage for receiving the carton from the table 67 when pushed therefrom by the pusher 94, which pocket comprises the relatively fixed side walls 116, 117, and the reciprocating expeller 118 movable laterally 70 of the machine, which expeller is operated to push the carton off from the carriage 93 into the delivery chute (to be hereinafter described) on the table 67, after three of the flaps have been folded and the paste applied to the fourth top flap.
- The means for moving the expeller outwardly comprises the cam 119 on the sleeve 120 slidably keyed to the shaft 29, which cam engages a stud or roller 121 on the long arm 122 of a rocking lever pivoted at 123 to the main frame and connected at its free end to the slide 124 of the expeller 118. The expeller is moved inwardly by a cam 125 on the sleeve 120, which cam engages a stud 80 or roller 126 on the short arm 127 of said rocking lever. Means are carried by the side walls 116, 117, of the pocket for folding two opposite top flaps of the carton, said means including the wings 128, 129, hinged, 90 respectively, at 130, 131, to the upper arms 132, 133, of two rocking levers pivoted at 134, 135, to the carriage 93, the lower arms 136, 137, of which levers are provided with studs or rollers 138, 139, engaging the faces 95 of the cams 140, 141, on the rotary sleeve 120. The wings 128, 129, are provided with arms 142, 143, which are connected to the upper ends of cam rods 144, 145, by links 146, 147, which cam rods slide in suitable 100 guides on the said two rocking levers. The lower ends of these cam rods 144, 145, are provided with studs or rollers 148, 149, engaging the peripheries of the cams 150, 151, on the sleeve 120. 105
- 110 Springs 152, 153, engaging the cam rods 144, 145, serve to hold the studs or rollers 148, 149, on the cams 150, 151, and tend to swing the wings 128, 129, upwardly into their opened positions.
- A spring 154 serves to hold the studs or rollers 138, 139, of the rocking levers against their cams 140, 141, and tends to swing the upper arms of said levers toward each other. 115
- Means are carried by two brackets 155, 156, uprising from the top of the carriage 93, for folding the third top flap of the carton over the two above-named top flaps, which means includes a wing 157 pivoted to said brackets 155, 156, and provided with 120 an arm 158 connected to the upper end of a rod 159, the lower end of which is connected to a cam lever 160 hinged at 161 to the carriage and provided with a stud or roller 162 engaging the periphery of a cam 163 on the 125 rotary sleeve 120. A spring 164 engages said rod 159 and serves to hold the stud or roller 162 on the cam 163 and tends to swing the wing 157 upwardly into its open position.

It is to be understood that the rotary sleeve 120 is moved along the shaft 29 with the carriage 93.

On the table 67 beyond the pusher 94 there is located an open ended delivery chute for receiving the cartons from the folding and sealing carriage 93, which chute is arranged laterally of the table 67 and comprises the side walls 164, 165, uprising from the table 10 and a top composed of a series of anti-friction rollers 166, arranged in position to engage the sealed tops of the cartons as they are expelled from the folding and sealing carriage by the expeller 118. The anti-friction roller 166 nearest the folding and sealing carriage serves to coact with the expeller to fold over and seal the fourth top flap of the carton as the carton is pushed into the chute beneath said roller by the 20 expeller.

The carton may or may not be provided with the wrapper 167 shown in Figs. 21 to 24; inclusive. When it is provided with the wrapper, the carton is preferably passed 25 through the machine, turned halfway around from the position which it occupies when being passed through the machine without the wrapper, thus changing the relative folding of the third and fourth top flaps.

30 The top flaps of the carton are denoted by 168, 169, 170, 171, and they form the extensions, as usual, of the four sides 172, 173, 174, 175, respectively, of the body portion of the carton. The tongued top flap 169 of the 35 carton has a slightly different shape when the carton is provided with the wrapper 167 so that the folding in of the wrapper with the top flaps is facilitated.

Proceeding to describe the operation of 40 this invention it will be first observed that the paster mechanism other than the paste applying arm, may be driven continuously through the shaft 1 whether the balance of the machine is or is not being operated, thus 45 preventing the gumming up or hardening of the paste. This will insure a more even transfer of the paste to the segment on the rotary arm of the paste applying device.

When the machine is operating for folding 50 and pasting, the filled cartons, with their open tops, are fed into the receiving end of the skeleton guide by the endless belt carrier where they come under the control of the carton advancing means, levers of which 55 alternately frictionally engage and release the cartons through the operation of the wedge-shaped cam 78 of the lever carriage 76 upon the lower arms 83, 84 of said levers. As each carton is advanced along the skeleton 60 guide toward the delivery end of the same, the converging guides 69, 69, will engage the two opposite sides of the open top of the carton and true the same up. The carton is then forced out through the delivery end of the skeleton guide by the suc- 65

ceeding cartons onto the table 67 against the wall 68 and in front of the pusher 94. The carton will press back the projecting arm 106 of the pusher controlling lever thereby causing the locking pin 108 to lock 70 the upper pusher slide 95 to the lower slide 96, which lower slide is connected to and operated by the lever 98, 104. In the meantime, the folding and sealing carriage 93 has been moved into position to bring its carton receiving pocket opposite the pusher 94 and there brought to rest by the coaction of the blank surfaced mutilated gears 38, 39. As the pusher is moved forwardly it will push the carton off from the table 67 into the pocket 80 on the carriage 93. As the carriage starts toward the delivery end of the machine the folding wings 128, 129, will start the folding of the top flaps 168, 170. Where the carton is not provided with the wrapper 167, the 85 wing 159 will start to fold the flap 169 down onto the flaps 168, 170. After these three top flaps have been folded, the paste will be applied to the inner face of the top flap 171 by the segment 62 of the rotary paste applying arm 61. The movement of the carriage 57, which supports the rotary paste applying arm 61, bears such a relationship to the movement of the carriage 93 that the paste will be applied to the inner face of the 90 top flap 171 of the carton by a rolling motion of the segment 62 over said flap. In the meantime, the folding wings 128, 129, have been withdrawn by the swinging movement of the upper arms 132, 133, of the two rocking levers, to which the wings are hinged. As the carriage reaches the limit of its movement toward the delivery end of the machine, the carton carried by its pocket will be brought opposite to the delivery chute 105 and the expeller 118 is operated to push the carton off from the carriage 93 onto the table 67 into the delivery chute beneath the anti-friction rollers 166. This movement of the carton will draw it from beneath the 110 wing 157 and will cause the first anti-friction roller 166 to fold the fourth top flap 171 down onto the other flaps and seal the same. By the time the carton has passed entirely through the delivery chute beneath 115 the several anti-friction rollers, the top of the carton will have been thoroughly sealed. Any suitable means may be employed for receiving the folded and sealed cartons from the delivery chute. When the carton is provided with the wrapper 167, the flap 171 is folded down over the flaps 168, 170, and the tongued flap 169 is the one which receives the paste and is the last one folded.

From the above description it will be seen 125 that the cartons are moved through the machine in successive longitudinal, lateral, longitudinal and lateral paths, a reciprocating friction means being employed for advancing the cartons along their first-named 130

longitudinal path a reciprocating device being employed for moving the cartons along their first-named lateral path, a reciprocating device being employed for moving the 5 cartons along their second-named longitudinal path and a reciprocating device being employed for moving the cartons along their second-named lateral path; the first three top flaps of the carton being folded and adhesive 10 applied to the fourth top flap while the carton is passing along its second-named longitudinal path, the fourth top flap being folded and sealed while the carton is passing along its second-named lateral path. 15 This arrangement permits a very rapid and effective folding and sealing of the carton, the correlation and arrangement of the parts being such as to produce a very compact machine with a minimum number of operating 20 parts.

It furthermore permits the continuous running of the pasting mechanism irrespective of the operation of the balance of the machine, thus preventing the hardening of 25 the paste and its ineffective application when the whole machine is running.

It will also be seen that the carton must be accurately placed in front of the pusher before the pusher can be interlocked with 30 its reciprocating means, thus preventing any damage to the carton if inaccurately placed in front of said pusher.

The novel movement of the first two flap folding wings, whereby they are swung 35 down into their folding position and then withdrawn from the top of the package, in such position, permits a very rapid folding of the top of the carton, the folding of the third flap not requiring the withdrawal of 40 the folding means for the first two top flaps before its operation is started.

It is evident that changes might be resorted to in the form, construction and arrangement of the several parts without de- 45 parting from the spirit and scope of our invention; hence we do not wish to limit ourselves strictly to the structure herein set forth, but

What we claim is:—

50 1. In a machine of the character described, a carton guide, reciprocating means intermittently gripping the cartons for advancing them along said guide, and converging guides for truing up the flaps at the open 55 tops of the cartons as they are advanced.

2. In a machine of the character described, a carton guide, a reciprocating carriage, levers thereon having arms for frictionally advancing the cartons along said guide and a cam movable on the carriage for controlling the action of said levers.

3. In a machine of the character described, a skeleton carton guide and means for intermittently advancing the cartons along the

guide comprising a reciprocating carriage, oppositely arranged levers carried thereby having arms projecting through the open sides of the guides for engaging the cartons, and a cam movable on and with the 70 carriage for controlling the action of said arms.

4. In a machine of the character described, a longitudinally arranged carton guide, a laterally movable pusher, and reciprocating 75 means intermittently gripping the cartons for advancing the cartons along the guide into position in front of the pusher.

5. In a machine of the character described, a longitudinally arranged carton guide, a 80 laterally movable pusher, friction means for intermittently advancing the cartons along the guide into position in front of the pusher, and a reciprocating folding and sealing carriage for receiving the cartons from 85 the pusher.

6. In a machine of the character described, a carton guide, a pusher and its reciprocating means, means for advancing successive cartons along the guide into position in front 90 of the pusher, and means controlled by the cartons for locking the pusher to its reciprocating means including a locking pin and a rocking lever.

7. In a machine of the character described, 95 a carton guide, a pusher and its reciprocating means including a locking pin and its operating lever, and means for advancing successive cartons along the guide into engagement with said lever in front of said 100 pusher whereby the movement of the lever will cause the pin to interlock the pusher and its reciprocating means.

8. In a machine of the character described, 105 a carton guide, a pusher and its reciprocating means including upper and lower slides, a locking pin and its operating lever and means for advancing successive cartons along the guide into engagement with said lever in front of said pusher whereby the move- 110 ment of the lever will cause the pin to interlock the slides to bring the pusher under the control of its reciprocating means.

9. In a machine of the character described, a longitudinally arranged carton guide, a 115 laterally reciprocating pusher and its operating means, means for advancing the cartons along the guide into position in front of said pusher and a longitudinally reciprocating folding and sealing carriage having 120 a pocket for receiving the carton from the pusher.

10. In a machine of the character described, a longitudinally reciprocating folding and sealing carriage, laterally movable 125 means for feeding a carton thereto when the carriage is in one position, laterally movable means for expelling the carton therefrom when the carriage is in another position, and means for causing the carriage to dwell an 130

- appreciable time at its receiving and expelling positions.
11. In a machine of the character described, a stationary support, a horizontally reciprocating folding and sealing carriage adjacent thereto, means on the support for feeding the carton in a lateral direction to the carriage when the carriage is in one position, means on the carriage for expelling the carton in a lateral direction when the carriage is in another position, and means for causing the carriage to dwell an appreciable time at its receiving and expelling positions.
12. In a machine of the character described, a stationary support, a longitudinally reciprocating folding and sealing carriage adjacent thereto, laterally movable means on the support for feeding a carton to the carriage when the carriage is in one position, laterally movable means on the carriage for expelling the carton when the carriage is in another position, and means for causing the carriage to dwell an appreciable time at its receiving and expelling positions.
13. In a machine of the character described, a reciprocating carriage having a pocket arranged to receive a carton with its top end flaps open and its bottom end flaps closed, a delivery chute, means for folding three of the top flaps of the carton, and carton expelling means coacting with the delivery chute for folding the fourth top flap of the carton.
14. In a machine of the character described, a reciprocating carriage having a carton receiving pocket, a delivery chute, means on the carriage for folding three of the top flaps of the carton, and carton expelling means on the carriage coacting with the delivery chute for folding the fourth top flap of the carton.
15. In a machine of the character described, a reciprocating carriage having a pocket arranged to receive a carton with its top end flaps open and its bottom end flaps closed, means for folding three of the top flaps of the carton, means for applying adhesive to the fourth top flap of the carton and carton expelling means for folding and sealing the said fourth top flap.
16. In a machine of the character described, a reciprocating carriage having a carton receiving pocket, means for folding three of the top flaps of the carton, another reciprocating carriage having means for applying adhesive to the fourth top flap, and carton expelling means for folding and sealing the said fourth top flap.
17. In a machine of the character described, a reciprocating carriage having a carton receiving pocket, means on the carriage for folding three of the top flaps of the carton, another reciprocating carriage having means for applying adhesive to the fourth top flap.
- fourth top flap of the carton and carton expelling means on the first-named carriage for folding and sealing the said fourth top flap.
18. In a machine of the character described, a reciprocating carriage having a pocket arranged to receive a carton with its top end flaps open and its bottom end flaps closed, a delivery chute, means for folding three of the top flaps of the carton, means for applying adhesive to the fourth top flap and carton expelling means coacting with the delivery chute for folding and sealing the fourth top flap.
19. In a machine of the character described, a reciprocating carriage having a carton receiving pocket, a delivery chute, means on the carriage for folding three of the top flaps of the carton, another reciprocating carriage having means for applying adhesive to the fourth top flap and carton expelling means on the first-named carriage coacting with the delivery chute for folding and sealing the fourth top flap.
20. In a machine of the character described, a reciprocating carriage having a carton receiving pocket, a pair of wings, means for rocking the wings to fold two opposite top flaps of the carton, means for folding the third and fourth top flaps and supports for the pair of folding wings and means for moving the supports to withdraw the wings in their folded position from under the third top flap.
21. In a machine of the character described, a reciprocating carriage having a carton receiving pocket, a pair of rocking levers pivoted on the carriage, wings pivoted on the levers, means for rocking the wings on the levers to fold two opposite top flaps of the carton, means for folding the third and fourth top flaps, and means for rocking the levers to withdraw the folding wings from under the third top flap.
22. In a machine of the character described, a reciprocating carriage having a pocket arranged to receive a carton with its top flaps open and its bottom flaps closed and cam controlled means movable with said carriage for folding the top flaps of the carton.
23. In a machine of the character described, a reciprocating carriage having a carton receiving pocket, a delivery chute having a series of anti-friction rollers along its top, means for folding three of the top flaps of the carton on the carriage and carton expelling means coacting with one of said anti-friction rollers for folding the fourth top flap.
24. In a machine of the character described, a reciprocating carriage having a carton receiving pocket, means on the carriage for folding three of the top flaps of the carton, means for applying adhesive to the fourth top flap.

the fourth top flap, a delivery chute having a series of anti-friction rollers along its top and carton expelling means coacting with one of said anti-friction rollers for folding 5 and sealing the fourth top flap.

25. In a machine of the character described, mechanisms for moving the cartons through the machine along successive longitudinal, lateral, longitudinal and lateral 10 paths, means for folding three of the top flaps and applying adhesive to the fourth top flap while the carton is passing along the second-named longitudinal path and means for folding and sealing the fourth top flap 15 while the carton is passing along its second-named lateral path.

26. In a machine of the character described, a longitudinally arranged carton guide, means for advancing the cartons along the same, a laterally movable pusher, 20 a longitudinally reciprocating carriage, a laterally movable expeller, a laterally arranged delivery chute, the advancing means, pusher, reciprocating carriage and expeller serving to move the carton through the machine, and means for folding and sealing 25 the carton.

In testimony, that we claim the foregoing as our invention, we have signed our names this 13th day of October 1915.

ERNEST A. SCHROEDER.
JOHN N. TOOKER.
